[57] **CLAIM**

The ornamental design for a housing for a photoelectric control, as shown and described.

DESCRIPTION

FIG. 1 is a front and top-right perspective view of a housing for a photoelectric control showing the new design; FIG. 2 is a front elevational view of the housing of FIG. 1; FIG. 3 is a rear elevational view of the housing of FIG. 1; FIG. 4 is a top plan view of the housing of FIG. 1; FIG. 5 is a bottom plan view of the housing of FIG. 1; FIG. 6 is a right side elevational view of the housing of FIG. 1, the left side housing being a mirror image of the right side housing; and, FIG. 7 is a rear and top-right perspective view of the housing of FIG. 1.

The broken-line portions of the housing are for illustrative purposes only and do not form part of the claimed design.
